[57] CLAIM

The ornamental design for a floral T-bar for a thong as shown and described.

DESCRIPTION

FIG. 1 is a top plan view of the floral T-bar for a thong, showing our new design;

FIG. 2 is a right side elevation view thereof;

FIG. 3 is a front elevation view thereof;

FIG. 4 is a top, rear and left perspective view thereof; and, FIG. 5 is a bottom plan view thereof.

The broken line showing of the thong base in the Figures is for illustrative purposes only and forms no part of the claimed design.

The broken lines which define the bounds of the claimed design form no part thereof.

The surfaces of the article not shown in the drawing or described in the specification forms no part of the claimed design.
